UNITED STATES PATENT OFFICE.

WILLIAM MENTOR NICHOLSON, OF ASHLAND, KENTUCKY.

DESIGN FOR A DISPLAY-STAND.

48,568.

Specification for Design. **Patented Feb. 15, 1916.**

Application filed December 10, 1915. Serial No. 66,206. Term of patent 14 years.

To all whom it may concern:

Be it known that I, **WILLIAM M. NICHOLSON**, a citizen of the United States, residing at Ashland, in the county of Boyd and State of Kentucky, have invented a new, original, and ornamental Design for Display-Stands, of which the following is a specification, reference being had to the accompanying drawing, forming part thereof.

The figure is a perspective view of a display stand, showing my new design.

I claim:—

The ornamental design for a display stand, as shown.

WILLIAM MENTOR NICHOLSON.

Witnesses:

ROBT. BINGHAM,
WILLIAM C. CARP.
